UNITED STATES PATENT OFFICE.

CHARLES M. MOGNI, OF NEW YORK, N. Y.

DRYER FOR PHOTOGRAPHIC PLATES.

1,071,943.

Specification of Letters Patent.

Patented Sept. 2, 1913.

Application filed April 27, 1910. Serial No. 557,853.

To all whom it may concern:

Be it known that I, CHARLES M. MOGNI, a citizen of the United States, residing at New York, in the county of New York and State of New York, have invented new and useful Improvements in Driers for Photographic Plates, of which the following is a specification:

My invention relates to driers, and more especially to that class of driers adapted to be used in the art of photography for drying photographic plates after the process of development has taken place.

My invention has for its object to provide a drying machine which may be easily and cheaply constructed, but which at the same time, shall be efficient in operation and positive in action.

With the foregoing and other objects in view, my invention consists of such details of construction and arrangement and combination of parts as will be hereinafter more fully described and specifically set forth in the appended claims.

In describing my invention in detail reference will be had to the accompanying drawings in which like reference characters denote like or corresponding parts throughout the several views, and in which:

Figure 1 is a view in side elevation of my invention; Fig. 2 is a view in elevation of one end of my invention; Fig. 3 is a sectional view taken on the line A-A of Fig. 1; Fig. 4 is a sectional detail view taken on the line B-B of Fig. 3 and, Fig. 5 is a detail view in perspective of the axle which retains the drying racks of my device.

In carrying my invention into practice, I first construct a frame work, one end of which consists of two uprights 1 which are erected upon a base member 2. The opposite end of the machine comprises two uprights 3 of less length which are erected upon a base member 4 similar to the member 2. The uprights or standards 1 and 3 are connected together in pairs by means of sills 5 and 6 respectively, and other sills 7 rest upon the sills 5 and 6 and extend from the uprights 1 to the uprights 3 thus forming a bed for the hangers 8 in which is journaled a shaft 9. Located centrally of the shaft 9 I provide an enlarged portion 10 having a plurality of oppositely located longitudinal slots 11 therein, at each end of which I preferably form holes 12 adapted

to removably receive rods 13 of such length as is adapted to receive the width of a photographic plate. The inner sides of the rods 13 are provided with longitudinal slots 14, which together with one of the slots 11 in the axle 9, forms a grooved rack which is adapted to receive a photographic plate of standard size. It will be readily appreciated that by increasing or decreasing the length of the slots in the member 10, and by adjusting the length of the rods 13, plates of various sizes may be inserted in my machine.

In order to hold the plates in place and prevent them from breakage due to centrifugal force and also to obviate the probability of dust settling upon the plates, I provide a cylindrical casing 15 which is made in two sections hinged together at 16 on one side, one of said sections being provided with a suitable latch or catch 17 adapted to firmly grasp a co-acting member upon the other section. This casing is of such construction that it may be disposed around the enlarged portion 10 of the shaft 9 in such manner that when the catch is engaged the casing will be securely held from independent rotation of its frictional contact with said portion 10. It is also advisable to provide some means to prevent movement of said casing longitudinally of the shaft 9, and in the drawings I have shown collars or angular flanges 18 formed on said shaft and disposed immediately outside of the opposite ends of said casing. It will be understood that any other suitable mechanical expedient may be resorted to for accomplishing this same result.

Mounted upon and extended through the end of the shaft 9 is a pulley 19 by which the drying portion of my invention may be operated from a suitable source of power. I desire it to be understood that any source of power may be employed such, for instance, as a water motor or electric motor. However, in practice I find hand power to be very satisfactory, and as it greatly simplifies my invention and enables me to place it upon the market at a low initial cost, I have shown a suitable driving mechanism for my machine. This driving mechanism comprises a shaft 20 journaled near the upper ends of the uprights or standards 1, said shaft having fixed thereon a cog wheel or sprocket 21 and being provided with a handle 22 of usual construction. A second

110

shaft 23 is journaled in proximity to the shaft 20 and is provided with a pinion 24 so disposed as to mesh with the wheel 21. Fixed upon the outer end of the shaft 23 is a pulley 25 similar to the pulley 19, but preferably somewhat larger in size for obvious reasons. The pulleys 19 and 25 may be connected by a belt 26 or any other suitable means for transmitting motion from one to the other.

It will be understood, of course, that this device is primarily designed to dry the film on plates, and that, after washing, surplus moisture is first allowed to drip off the plates before they are inserted in the machine, but it will be readily appreciated that plates just washed may be inserted in the drier by providing any suitable means for drawing off, or preventing the accumulation, along the edges of the plates, of the surplus moisture which will be thrown outward during the operation of the machine. As this feature forms no part of my present invention it has not been illustrated.

From the foregoing it will be seen that I have provided a very simple drying device which may be easily operated and which costs little to manufacture. In practice I have found it to be very efficient.

I desire it to be understood that slight changes in construction and in the arrangement and combination of parts may be resorted to without deviating from the spirit of my invention provided such changes fall within the scope of the appended claims.

Having thus fully described my invention, what I claim as new and desire to secure by Letters Patent, is,

1. A drier for photographic plates comprising a frame, an axle journaled thereon, means to rotate said axle, racks extending radially from said axle, a casing mounted to rotate with said axle and to inclose said racks, said casing comprising a plurality of sections hinged to each other, and means to fasten said sections together.

2. A drier for photographic plates, comprising a frame, an axle journaled thereon, means to rotate said axle, a perforated casing mounted on said axle to rotate there-

with, and article support means interior of said casing.

3. A drier comprising a frame, an axle journaled thereon, means to rotate said axle, a casing comprising a plurality of sections, means to removably mount said casing on said axle, and article support means interior of said casing.

4. A drier comprising a frame, an axle 60 journaled thereon, a casing mounted on said axle, said casing comprising a plurality of sections hinged to each other, means to position said casing on said axle, and article support means mounted on said axle and located interior of said casing.

5. A drier for photographic plates comprising a frame, an axle journaled thereon, a casing mounted on said axle to rotate therewith, rods extending downwardly from said axle, said rods having grooves therein providing means for retaining the plates, and means to rotate said axle.

6. A drier for photographic plates comprising a frame, an axle journaled thereon, said axle having grooves extending longitudinally thereof, rods extending outward from said axle, said rods having grooves coinciding with the grooves in said axle, said grooves forming a rack adapted to receive the plate, and means for rotating said axle.

7. A drier for photographic plates comprising a frame, an axle journaled thereon, means carried by said axle for holding the plates, a casing frictionally held on said axle, said casing adapted to retain said plates in position, and means for rotating said axle.

8. A drier comprising a frame, an axle journaled thereon, an enlarged portion on said axle having enlarged spaced apart portions thereon, a casing comprising hinged sections mounted on said first enlarged portion intermediate the spaced apart enlarged portions, fastening means for the casing sections, and article supporting means interior of the casing projecting from the first enlarged portion.

CHARLES M. MOGNI.
